US0D1111015S

(12) **United States Design Patent** (10) **Patent No.:** **US D1,111,015 S**
(45) **Date of Patent:** **** Feb. 3, 2026**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Arian Behzadi**, San Francisco, CA (US); **Imran Chaudhri**, San Francisco, CA (US); **Patrick Lee Coffman**, San Francisco, CA (US); **Jonathan Dascola**, San Francisco, CA (US); **Alan C. Dye**, San Francisco, CA (US); **Christopher Foss**, San Francisco, CA (US); **David C. Graham**, Campbell, CA (US); **Jonathan P. Ive**, San Francisco, CA (US); **Stephen O. Lemay**, Palo Alto, CA (US)

(73) Assignee: **Apple Inc.**, Cupertino, CA (US)

(**) Term: **15 Years**

(21) Appl. No.: **29/899,259**

(22) Filed: **Aug. 7, 2023**

Related U.S. Application Data

(63) Continuation of application No. 29/787,459, filed on Jun. 7, 2021, now Pat. No. Des. 994,684, which is a continuation of application No. 29/727,474, filed on Mar. 11, 2020, now Pat. No. Des. 921,672, which is a continuation of application No. 29/645,911, filed on Apr. 30, 2018, now Pat. No. Des. 882,607, which is a continuation of application No. 29/567,760, filed on Jun. 13, 2016, now Pat. No. Des. 819,067.

CLAIM

The ornamental design for a display screen or portion thereof with graphical user interface as shown and described.

DESCRIPTION

The sole FIGURE shows a display screen or portion thereof with graphical user interface showing our new design. The peripheral dashed broken lines depict a display screen or portion thereof, and form no part of the claimed design. The dashed broken lines within the peripheral dashed broken lines depict portions of the graphical user interface which form no part of the claimed design.
